VAPORIZING DEVICE

Charles F. J. Dupuy, Mahwah, N. J., assignor to
O-Cedar Corp'n, Chicago, Ill., a corporation of
Illinois

Application February 28, 1944, Serial No. 524,164

5 Claims. (Cl. 299—20)

This invention relates to a vaporizing device, and more particularly to a device for vaporizing liquids in which the quantity of liquid vaporized may be readily controlled.

An object of the invention is to provide a simple and effective device for vaporizing liquids. The device may be used in deodorizing air or odorizing air, in disinfecting air, and in inhibiting or destroying moths or other insects. Another object is to provide in a vaporizing device, simple means for controlling the quantity of liquid vaporized. Still another object is to provide a device which is easy to assemble and may be readily taken apart or disassembled. A further object is to provide a vaporizing device which may include a pad saturated with liquid and in which the pad is freely accessible to the air while at the same time liquid may not overflow or escape from the pad and from the container.

A still further object is to provide a vaporizing device in which the rate of vaporization can be varied by adjusting the access to the air.

Other features and advantages are set forth in the following specification and drawing, in which—

Fig. 1 is a side elevational view of the device; Fig. 2 is a vertical sectional view taken along the line 2—2 of Fig. 1; Fig. 3 is a transverse sectional view taken along the line 3—3 of Fig. 2; Fig. 4 is a transverse sectional view taken along the line 4—4 of Fig. 2, and Fig. 5 is a vertical section of a modified construction.

The invention contemplates a vaporizing device in which a liquid container may be equipped with one or more capillary members extending into the liquid in a container and communicating with a vaporizing pad. The exposure of the pad and access of the air thereto determines the quantity of liquid which is vaporized and imparted to the air, and this exposure is controlled by a closure member in the device.

The vaporizing device of Figs. 1 to 4 includes a liquid container 10 of any suitable or conventional structure and having a large opening 11 in the upper portion thereof. Liquid 12 may be placed in the container and may be at any suitable level, such, for example, as the level 13 seen in Fig. 2. The wicks 14 are received within the liquid in the container and extend upwardly into the opening or mouth 11 of the container.

A plate 15 is received within the opening 11 in the container 10 and provides a base for supporting a vaporizing pad 16 which is connected or communicates with the wicks 14. The pad 16 and

the wicks 14 may be of conventional construction of the type used in vaporizing devices.

The container may be equipped with a depressed annular rim 17 extending about the opening 11. The plate 15 in turn is provided with a laterally-extending flange 18 which is received on the rim 17 to support the plate in the container. The rim 17 may be equipped with a plurality of notches 19 which are adapted to receive corresponding lugs 20 on the plate 15 so as to prevent rotation of the plate 15 with respect to the container while permitting the plate 15 to be readily removed from the container by lifting it upwardly.

The plate 15 is preferably provided with a recessed portion 21 having a central aperture 22 therein. The recessed portion of the plate is preferably of a depth substantially the same as the thickness of the pad 16 so that the pad 16 does not extend above the upper surface of the flange 18 of the plate. The central aperture 22 in the plate permits the wicks 14 to extend therethrough into communication with the pad 16.

An annular upwardly-extending peripheral flange 23 on the plate 15 is provided with a plurality of circumferentially-spaced apertures 24 therein. As illustrated in Fig. 2, the flange may consist of a plurality of lugs 25 substantially uniformly spaced apart about the circumference of the outer periphery of the plate. A closure 26 extends over the plate 15 and is provided with a depending peripheral flange 27 which is received in adjacent concentric relation with respect to the flange 23 of the plate. The depending flange 27 may consist of a plurality of lugs 28 substantially uniformly spaced apart about the circumference of the closure by the openings or apertures 29, or the flange may be equipped with any suitable type of aperture. As illustrated, the depending flange 27 is received about the outwardly-extending flange 23 and is supported upon the upper surface of the container. The closure 26 which is freely removable from the container is also rotatable thereon so that the openings 29 may be brought into and out of register with the openings 24 in the flange 23.

In operation, the container 10 is filled with the liquid to be vaporized to a suitable level, such as the level 13. The removable plate 15 is then placed in the opening 11 in the container, with the lateral flange 18 supported upon the depressed rim 17 of the container and the projections 20 being received within the notches 19 in the rim 17. The plate 15 thus is locked against rotation with respect to the container by reason of the

interlocking engagement of the projections 20 with the notches 19, but at the same time is readily removable from the container by lifting the plate upwardly therefrom. The pad 16 carrying the wicks 14 is placed on the plate 15 with the wicks extending downwardly through the central aperture in the plate 15 into the liquid 12 in the container 10.

With the pad and wicks in position, the liquid which is absorbed by the wicks flows upwardly into the pad and vaporizes therefrom. If the closure is not in position, the entire upper surface of the pad is exposed to the air and the liquid in the pad readily vaporizes into the air.

When it is desired to control the quantity of vapor imparted into the air, the closure is placed into position over the plate 15 and the openings or apertures 29 may be in register with the apertures 24. In this position, a circulation of air is permitted across the upper surface of the pad 16 and liquid is thus vaporized from the pad. By rotating the closure 26, the size of the registering openings may be adjusted and, in fact, if desired, the openings may be entirely out of register so that the air between the pad and the closure cannot escape. By thus controlling the flow of air above the pad, the quantity of vapor imparted to the air may also be controlled.

Figure 5 illustrates an alternative construction including a liquid container 31 of a convenient size and formed of any material which will hold a liquid. At its upper end the container is formed with an inwardly extending flange 32 which is preferably depressed below the level of the container top. An upstanding peripheral flange 33 is formed on the upper part of the container and is provided with a plurality of circumferentially spaced apertures 34 therein.

The vaporizing unit in this construction is formed of a porous material such as unglazed porcelain, porous wood or the like. The unit as shown includes a pad portion 35 which is circular in outline to rest on the depressed flange 32 with its upper surface substantially flush with the top of the container. A capillary portion 36 integral with the pad portion 35 depends therefrom into the liquid in the container so that liquid will be drawn up to the pad portion by capillary action.

The container is closed by a cover or closure 37 having a downwardly extending peripheral flange 38 formed with a series of spaced apertures of substantially the same width as the apertures 34. The cover fits loosely over the top of the container with its flange 38 overlying the flange 33 so that the cover is rotatably supported on the container.

In use liquid in the container flows upwardly through the capillary portion 36 of the vaporizing unit into the pad 35 and vaporizes therefrom. The closure may be removed for exposure of the entire upper surface of the pad to the air for rapid vaporization or with the cover in place it may be turned to make more or less of the openings 34 effective so that the rate of vaporization can be controlled.

While two embodiments of the invention have been shown and described in detail herein, it will be understood that these are illustrative only and are not intended as definition of the scope of the invention, reference being had for this purpose to the appended claims.

What is claimed is:

1. A vaporizing device comprising a liquid con-

tainer having an open top, an upstanding peripheral flange at the top of the container formed with a series of spaced apertures, a porous pad supported adjacent the top of the container interior to the flange with its upper surface below the bottoms of the apertures, a capillary member depending from the pad into the container, a cover rotatably supported on the container, and a depending peripheral flange on the cover overlying the first named circular flange and formed with a series of spaced apertures variably to register with the first named apertures as the cover is turned.

2. A vaporizing device comprising a liquid container having an opening in the upper portion thereof, a base extending about said opening and being recessed below the upper surface of the container, a porous pad fitting within the recess on the base of a thickness such that its upper surface is substantially flush with the upper surface of the recess, a capillary member depending from the pad into the container, an upwardly-extending peripheral flange on said base, said flange being provided with a plurality of circumferentially-spaced apertures, and a closure removably received on said base and covering the same, said closure being equipped with a depending peripheral flange disposed in adjacent concentric relation with the flange of the base, said depending flange being equipped with a plurality of circumferentially-spaced apertures therein, the closure being rotatable on the container to bring said apertures into and out of register with each other.

3. A vaporizing device comprising a liquid container having an opening in the upper end thereof, a centrally-apertured plate removably received within said opening and closing the same, said plate being provided with a recessed portion disposed below the upper surface of the container and adapted to receive a vaporizing pad thereon, an upwardly-extending peripheral flange on said plate extending upwardly above the upper surface of the container, said flange being provided with a plurality of circumferentially-spaced apertures therein, and a closure removably supported by the container above said plate and equipped with a depending peripheral flange disposed in adjacent concentric relation with respect to the flange on said plate, said depending flange being equipped with a plurality of circumferentially-spaced apertures therein, the closure being rotatable with respect to the plate to bring said apertures into and out of register with each other.

4. A vaporizing device comprising a liquid container having an opening in the upper end thereof, an annular rim extending inwardly about said opening and slightly below the upper surface of the container, a plate received on said rim and having its upper surface substantially flush with the upper surface of the container, said plate being centrally apertured and adapted to receive a vaporizing pad thereon, the central aperture in the plate communicating with the interior of the container, said plate being received in interlocking relation with said rim to prevent rotation of the plate within the container while permitting the removal of the plate by vertical movement thereof, a recessed portion in said plate about said central aperture therein for receiving a vaporizing pad below the upper surface of the container, a plurality of upwardly-extending peripheral flange segments on said

plate extending upwardly above the upper surface of the container, said segments being circumferentially and substantially uniformly spaced apart by distances substantially equal to the width of the segments, and a closure removably supported on the container above said plate and equipped with a plurality of depending peripheral flange segments, said depending segments being substantially uniformly spaced apart by the same distance as the distance by which the upwardly-extending segments are spaced apart and being received in adjacent concentric relation with respect to said upwardly-extending segments, said closure being rotatable with respect to said container whereby the spaces between said segments may be brought into and out of register with each other.

5. A vaporizing device comprising a liquid con-

10 tainer having an open top, an inwardly extending flange at the top of the container lying below the top of the container, a porous vaporizing unit including an upper pad portion adapted to overlie and be supported on the flange with its upper surface substantially flush with the top of the container and a depending capillary portion to extend into a body of liquid in the container, an upstanding peripheral flange on the top of the container formed with a series of spaced apertures, a closure rotatably supported on the top of the container, and a depending peripheral flange on the closure overlying the upstanding flange and formed with a series of apertures 15 variably to register with the apertures in the upstanding flange as the closure is turned.
